UNITED STATES PATENT OFFICE.

SAMUEL H. RICE, OF SAN FRANCISCO, CALIFORNIA, ASSIGNOR TO KALAMAZOO LOOSE LEAF BINDER CO., OF KALAMAZOO, MICHIGAN.

BINDER DEVICE.

1,288,991.

Specification of Letters Patent. Patented Dec. 24, 1918.

Original application filed June 15, 1917, Serial No. 174,919. Divided and this application filed August 1, 1917. Serial No. 183,935.

To all whom it may concern:

Be it known that I, SAMUEL H. RICE, a citizen of the United States, residing at San Francisco, county of San Francisco, State of California, have invented certain new and useful Improvements in Binder Devices, of which the following is a specification.

This invention relates to improvements in binder devices.

10 The main objects of this invention are:

First, to provide an improved binder device which facilitates the use of temporary binders or loose sheet holders, and particularly those used in machine accounting systems.

15 Second, to provide an improved binder which facilitates the handling or manipulation of loose record sheets.

Third, to provide an improved binder device which facilitates the manipulation and handling of temporary binders for the insertion and removal of the sheets therefrom.

20 Further objects, and objects relating to structural details, will definitely appear 25 from the detailed description to follow.

I accomplish the objects of my invention by the devices and means described in the following specification. The invention is clearly defined and pointed out in the claims.

30 A structure which is a preferred embodiment of my invention is clearly illustrated in the accompanying drawing, forming a part of this specification, in which:

Figure I is a perspective view of the holder 35 of my improved binder device with the binder removed; the holder being in its partially collapsed position.

Fig. II is a view, partially in vertical transverse section, with the holder adjusted 40 to support the binder in its closed position.

Fig. III is a view similar to that of Fig. II, illustrating the holder supporting a binder with a less number of sheets than that shown in Fig. II.

45 Fig. IV is a view similar to that of Figs. II, and III, showing the holder supporting a binder with still fewer sheets.

Fig. V is a perspective view showing the holder members adjusted to receive the 50 binder members and the binder members arranged therein, the sheets being all arranged on one binder member.

Fig. VI is a transverse vertical section

with the center or supplemental member in position, part of the sheets being arranged 55 in each holder member.

Fig. VII is a perspective view with the holder in extended position and the central or supplemental holder member in position.

In the drawing similar reference characters refer to similar parts throughout the several views.

In the embodiment illustrated I provide a rectangular frame or base comprising sides 1, ends 2, and legs or corner uprights 65

3. The holder members, designated generally by the numerals 4 and 5, are pivoted at 6 between the end members of the frame or base. These holder members comprise the side members 7 and 8 and coacting end 70

members 9 and 10, respectively. The end members and the side members of the structure illustrated are disposed at right angles to each other, the width of the end members being such that their edges clear when the 75

holder members are swung to their collapsed or extended positions. The inner ends of the side members 7 and 8 are extended to provide stops 11 and 12 respectively. When the holder members are swung to their ex- 80

20 tended position, as shown in Fig. VI, these stops engage coacting stops 13 and 14 on the base or frame. When the holder members are fully collapsed the end member 10 engages the stop 14, while the end member 85

9 engages the stop 15.

When swung to their erected positions, as shown in Figs. II, III and IV, the side members will engage the covers of a binder resting upon the end members, supporting it in 90

closed position, the weight of the binder resting on the end members within the pivots 6 tending to press the sides against the covers.

From the illustrations of Figs. II, III and 95 IV, it will be seen that the holder automatically adjusts itself within its scope to binders of varying thickness.

When the holder members are extended they provide a pair of V-shaped holders 100 each adapted to receive one of the binder members 16 which comprise covers 17 and binding or clamping bars 18 connected by the binding strips 19.

The sheets 20 have notches 21 in their inner edges adapted to receive the binding

strips when the binder is closed. The sheets are also provided with holes 22 adapted to receive removable posts 23, substantially as shown in the Wigginton Patent #1,174,458, 5 March 7, 1916. The end members are transversely slotted at 24 to receive these binding strips when adjusted to the position shown in Fig. V.

To complement or supplement the end members when adjusted to the position shown in Figs. V, VI and VII, I provide an A-shaped central or supplemental end member 25 having arms 26 and 27 secured to each other. The arm or part 26 of this 15 supplemental member is adapted to edge-abut the end member 10, while the other arm 27 overlaps the end member 9, as clearly shown in Fig. VI, and abuts the filler block 28 disposed in the angle of the holder member 4. The filler or supplemental member is provided with hand holds 29 and with dowels 30 connecting it with the end member 10.

In the structure illustrated the part 27 is 25 disposed at an acute angle to the side 7, so that fanning or stepping of the upper edges of the sheets is secured to facilitate the finger-gripping.

With this arrangement of parts, I secure 30 a structure which may be readily adjusted to provide a pair of V-shaped holders adapted to support the binder members with sheets resting thereon so that the loose sheets 20 may be transferred from one binder member 35 to the other. This greatly facilitates the manipulation of the sheets in the making of records. To assist in alining the sheets on the holder members the supplemental member 25 is provided with guide ribs 31 with 40 which the notches of the sheets may be engaged.

I have not attempted to illustrate or describe certain modifications in structural details which I contemplate, as I believe the 45 disclosure made will enable those skilled in the art to which my invention relates to embody or adapt the same as may be desired.

The structural details of the binder are not illustrated as they form no part of my 50 present invention.

Claims to the holder proper are made in my application for Letters Patent, filed June 15, 1917, Serial No. 174,919, this application being a division of such application.

Having thus described my invention, what I claim as new and desire to secure by Letters Patent; is:

1. In a structure of the class described, 60 the combination of a binder comprising separably associated binder members and binding strips extending between said members, of a pair of coacting holder members each comprising a side and end member and mounted for adjustment to provide a pair

of holders each adapted to receive one of the binder members with sheets resting thereon or to support the binder in its closed position resting upon the end members and the side members engaging the sides thereof, 70 the said end members being slotted to receive the binding strips when the parts are in their extended position, and a removable supplemental member coacting with said end members and having a sheet guide thereon. 75

2. In a structure of the class described, the combination of a binder comprising separably associated binder members and binding strips extending between said members, 80 of a pair of coacting holder members each comprising a side and end member and mounted for adjustment to provide a pair of holders each adapted to receive one of the binder members with sheets resting thereon or to support the binder in its closed position resting upon the end members and the side members engaging the sides thereof, the said end members being slotted to receive the binding strips when the parts are in their extended position. 85

3. In a structure of the class described, the combination of a binder comprising separably associated binder members, of a pair of coacting holder members each comprising a side and end member and mounted 90 for adjustment to provide a pair of holders each adapted to receive one of the binder members with sheets resting thereon or to support the binder in its closed position resting upon the end members and the side members engaging the sides thereof, and a removable supplemental member coacting with said end members and having a sheet guide thereon. 95

4. In a device of the class described, the combination with loose sheets of a binder therefor comprising separably associated binder members, a pair of holder members each comprising side and end members and pivotally mounted for adjustment to an upright or to an outwardly inclined relation and forming, when adjusted to an upright position, a holder for the closed binder and, when adjusted to their outwardly inclined relation, a pair of holders each adapted to receive one of the binder members with sheets resting thereon, the width of the end members being such as to permit them to clear when swung to and from their outer positions, and a removable A-shaped supplemental member. 105

5. In a structure of the class described, the combination of a binder comprising separably associated binder members, of a pair of coacting holder members each comprising a side and end member and mounted for adjustment to provide a pair of holders each adapted to receive one of the binder members with sheets resting thereon or to support the binder in its closed position 110

120

125

130

- resting upon the end members and the side members engaging the sides thereof, the side and end members of one holder member being disposed at right angles so that sheets 5 may be disposed on said binder member in a rectangular pile resting thereon abutting its end member.
6. In a device of the class described, the combination with loose sheets of a binder 10 therefor comprising separably associated binder members, a pair of holder members each comprising side and end members and pivotally mounted for adjustment to an upright or to an outwardly inclined relation 15 and forming, when adjusted to an upright position, a holder for the closed binder and, when adjusted to their outwardly inclined relation, a pair of holders each adapted to receive one of the binder members with 20 sheets resting thereon, the side and end members of one holder member being disposed at right angles so that sheets may be disposed on said binder member in a rectangular pile resting thereon with their 25 ends abutting its end member.
7. In a device of the class described, the combination of a binder comprising separably associated binder members, a pair of holder members each comprising side and 30 end members and pivotally mounted for adjustment to an upright or to an outwardly inclined relation and forming, when adjusted to their upright position, a holder for the closed binder and, when adjusted to an 35 outwardly inclined relation, a pair of holders each adapted to receive one of the binder members, the side and end members of one holder member being disposed at right angles so that sheets may be disposed on said 40 binder member in a rectangular pile resting thereon with their ends abutting its end member.
8. In a device of the class described, the combination with loose sheets, of a temporary binder therefor comprising a pair of 45 separably associated binder members, and a pair of holder members each comprising side and end members and mounted for pivotal adjustment to provide a pair of V-shaped 50 holders each adapted to receive a binder member with sheets resting thereon or to be swung to an upright position with the binder members resting upon the end 55 members and the side members engaging the sides thereof, the side and end members of one holder member being disposed at right angles so that sheets may be disposed on said binder member in a rectangular pile
- resting thereon with their ends abutting its end member. 60
9. In a device of the class described, the combination of loose sheets and a binder therefor comprising separably associated binder members, and a pair of holder members each comprising side and end members 65 and mounted for pivotal adjustment to provide a pair of holders each adapted to receive one of said binder members with sheets resting thereon or to be swung to an upright position with the side members engaging the side of the binder and the latter resting on the end members, the side and end members of one holder member being disposed at right angles so that sheets may be disposed on said binder member in a 70 rectangular pile resting thereon with their ends abutting its end member. 75
10. In a device of the class described, the combination of a binder comprising separably associated binder members, and a pair of holder members each comprising side and end members mounted for pivotal adjustment to provide a pair of holders each adapted to receive one of said binder members, or to be swung to an upright position with 80 the side members engaging the covers of the binder and the latter resting on the end members, the side and end members of one holder member being disposed at right angles so that sheets may be disposed on said binder member resting thereon with their 85 ends abutting its end member. 90
11. In a device of the class described, the combination with the loose sheets, of a binder therefor comprising a pair of separably associated binder members, and a holder comprising a pair of members mounted for adjustment to an oppositely inclined relation to provide a holder for each binder member and adapted to support the same 95 with sheets resting thereon or to an inwardly inclined relation to support the binder in a closed upright position, the side and end members of one holder member being disposed at right angles so that sheets may be disposed on said binder member in a rectangular pile resting thereon with their 100 ends abutting its end member. 100
- In witness whereof I have hereunto set my hand and seal in the presence of two witnesses. 105
